UNITED STATES PATENT OFFICE.

HARRY S. MOORE, OF BRIDGETON, NEW JERSEY, ASSIGNOR OF ONE-HALF
TO STANTON B. COLE, OF SAME PLACE.

MERRY-GO-ROUND.

SPECIFICATION forming part of Letters Patent No. 504,886, dated September 12, 1893.

Application filed June 22, 1892. Serial No. 437,612. (No model.)

To all whom it may concern:

Be it known that I, HARRY S. MOORE, a citizen of the United States, residing at Bridgeton, in the county of Cumberland and State of New Jersey, have invented certain new and useful Improvements in Merry-Go-Rounds; and I do hereby declare the following to be a full, clear, and exact description of the invention, such as will enable others skilled in the art to which it appertains to make and use the same.

My invention consists of an improvement in that class of devices known as merry-go-rounds and contains certain novel features of construction fully shown in the accompanying drawings and described in the specification following.

In the drawings Figure 1 is a perspective view of my improved device. Fig. 2 is a plan view of the gearing. Fig. 3 is a partial sectional view of the same. Fig. 4 is a detail view of my preferred form of bearing for the central gear wheel, and Fig. 5 is a sectional view of the ball bearing support for the frame.

One of the principal objects of my invention is to provide a swinging merry-go-round or one having a swinging and circular movement simultaneously.

Referring to the drawings in which similar letters of reference indicate identical parts throughout, A represents the main supporting pole or standard extending upward from a base to which it is rigidly secured, the top of which is provided with a recess *a* in which is placed a suitable bearing to receive the lower half of a ball, leaving the upper half exposed. A cap B is provided and adapted to fit the upper half of said ball. C is a ring of metal or other suitable material to which are rigidly secured the arms D, which may be made jointed if desired so as to occupy the smallest possible space for packing. The outer ends of the arms D may be secured together in any desired manner. From the outer extremities of the arms D to the outer edge of the cap piece B are extended supports *d* for an awning or other covering. From the arms D there are downwardly extending pieces *d'* which serve to support the circular base E upon which are placed chairs, wooden horses or other analogous devices to be used

by passengers. The circular base E is constructed in such a manner as to permit lateral movement to the frame, its central portion being removed for that purpose. A railing F may be placed if desired upon the outer edge of this circular base E for the purpose of increasing the safety of the passengers. Upon the supporting pole A at a point between the circular base E and the ring C, is revolvably mounted a large gear wheel G. To the upper side of this gear wheel G are attached brackets *g* at opposite points. In the outer end of this bracket is pivoted the pin *g'* having a divided head or upper end; a like pin *g''* is pivoted in two of the arms D. A link *h* is pivoted in the upper ends of the pins *g*, *g''*, so that the motion given to the gear wheel G is communicated to the frame of the machine and the seats or horses carried thereby. This connection while providing for the proper revolution of the main frame admits of any lateral movement which may be communicated thereto. Motion is imparted to the gear wheel G by the spur gear H' on a vertical shaft H provided with a beveled gear wheel at its lower extremity which meshes with a second beveled gear wheel mounted on a horizontal rod to which power is applied. Any form of gearing may however be used, and any mode of applying power, as these devices form no part of my invention. Above the gear wheel G upon the pole A there is revolvably mounted as shown in Fig. 4, a cog wheel I. In Fig. 4 of the drawings, I have shown a collar interposed between the wheels G and I. This collar may be loose and perform the function of a simple washer or it may be rigidly secured upon the standard and support the wheel I. Above the wheel I a bracket *I'* is rigidly secured to the standard. I prefer to form the bracket integral with and projecting from a collar surrounding the standard, but it may be secured to the standard in any other way. In order to secure the wheel I to the standard and hold it stationary, a pin *i* movable in an opening in the bracket *I'*, can be made to engage an aperture in the wheel I, holding the two in fixed relation, and preventing the movement of said wheel. In order to facilitate the manipulation of the pin *i*, I provide the same with a shank lying

in a groove in the standard within the wheels G and I as shown in the drawings. The lower end of the shank may be pivoted to a lever, said lever extending outwardly to some point 5 easy of access. The pin may be manipulated in any manner however. Meshing with the wheel I and mounted upon the wheel G as shown, on opposite sides thereof, are cog wheels I' I'. Similar cog wheels I² I² are mounted 10 in the same manner on the wheel G near its rim and gear with the wheels I' I'. To each of the gear wheels I² I² is rigidly secured a crank arm K K, having pivoted to them or near their outer extremities, rods or their 15 equivalents L L which are pivotally connected to two opposite arms D D of the frame of the machine.

In my preferred construction shown in Fig. 2, a spring is interposed at the point of connection of the rods L with the arms D to avoid any jar which might otherwise occur. It is obvious that the spring may be located with 20 equally as good effect at the point where the rod L connects with the crank arm K.

25 In Fig. 2, the wheels I² are shown as being smaller than the wheel I. This will give the swinging movement at intervals, less than one entire revolution of the wheel G and the frame. I prefer however, to form the wheels 30 I² of the same size as the wheels I and produce the swinging motion at opposite sides of the machine, or a to and fro motion at each entire revolution of the wheel G.

35 The mode of operation of my improved machine is obvious. Power being applied the gear wheel H is set in motion which meshing with the large wheel G rotates the frame of the machine upon the ball bearing a in the recess at the top of the pole A and 40 upon which bearing the entire frame is supported. As soon as the machine has acquired sufficient momentum in its circular motion, the pin i is depressed and made to engage the opening in the wheel I and forces the cog 45 wheel I to remain stationary. The stopping of the wheel I and the continued motion of the wheel G, sets in motion the gear wheels I' I', I² I², and consequently the crank arms K K which being secured to the main frame 50 of the machine by the intermediate arms L L give the machine a lateral motion at certain points in its rotation, thus making the frame and base swing simultaneously. The ring C is made of sufficient diameter to permit the 55 swinging movement to equal the length of the crank arms K K, and the cap B is mounted on its bearing in such a manner as shown in the drawings as will permit rotary movement in any direction.

60 In using the machine as an ordinary merry-go-round the cog wheels G and I rotate together, and in order to insure their unity of rotation, I provide a pin k bent at right angles as shown, the horizontal portion of which 65 projects from a collar M mounted loosely upon the standard, and adapted to be engaged by

the lugs i² i³ provided on the pin i. By this arrangement it will be observed that by raising the pin i the vertical part k' of the pin k will be thrust through suitable openings in 70 the wheels G and I and the part i' of the pin i be forced out of connection with the wheel I when the wheels G and I will rotate together. By lowering the pin i the part k' of the pin k will be forced out of engagement with the 75 wheel I and the part i' of the pin i into engagement with said wheel, holding it in rigid connection with the standard.

Having described my invention, what I claim, and desire to secure by Letters Patent, 80 is as follows:

1. In a merry-go-round, the combination with the main supporting pole or standard, of a frame supported from the top of the same, mechanism for imparting a rotary motion to 85 said frame and a separate mechanism having rigid connection with said frame for imparting a lateral movement to the same, substantially as described.

2. In a merry-go-round, the combination 90 with the supporting pole or standard, of a frame surrounding said pole or standard and supported from the top of the same, mechanism for imparting a rotary motion to said frame, and a separate mechanism including 95 a crank-pin and a rigid connection between the said crank-pin and said frame for imparting a lateral movement to the frame, substantially as described.

3. In a merry-go-round the combination 100 with a main supporting pole or standard, of a frame revolvably supported at or near the top of said standard, means for rotating said frame, crank pins, links connecting said crank pins with said frame, said links having universal connections with said pins and frame, and means for moving said crank pins whereby a reciprocating movement is given to said frame, which is greatest during the middle portion of said movement and decreases toward the extremes thereof, substantially as 110 described.

4. In a merry-go-round the combination 115 with the main supporting pole or standard, a frame surrounding the same and supported from the top thereof, a driving wheel having rigid link connections with said frame for imparting rotary motion thereto, cranks having rigid link connections with said frame for imparting lateral motion thereto and means 120 for operating said cranks and gear wheels, substantially as described.

5. In a merry-go-round the combination 125 with a main supporting pole or standard, of a frame supported from the top thereof, a driving wheel mounted on said standard having rigid link connections with said frame for imparting rotary motion thereto, cranks having rigid link connections with said frame for imparting lateral movement to the same, a 130 gear wheel mounted on said standard for imparting motion to said cranks and means for

connecting to and disconnecting from said pole, the crank operating wheel, substantially as described.

6. In a merry-go-round the combination with a supporting standard, of a frame revolvably supported at or near the top of said standard, said frame surrounding the standard below the point of suspension, a driving wheel having rigid link connections with said frame for imparting rotary motion thereto, said links having universal connections with the wheel and said frame permitting a lateral movement to be imparted to the frame, substantially as described.

15 7. In a merry-go-round the combination with a main supporting pole or standard, a main frame surrounding said supporting pole,

a main gear wheel mounted upon said supporting pole, gearing for imparting rotary motion to said frame, gearing mounted upon said main gear wheel, a crank arm movably connected by an intervening part with the main frame, a second gear wheel mounted upon the pole and meshing with the gearing mounted on said main gear wheel and means 20 for rigidly attaching said second gear wheel to and detaching it from the supporting pole, substantially as described.

In testimony whereof I affix my signature in presence of two witnesses.
